UNITED STATES PATENT OFFICE.

WILLIAM HUGERSHOFF, OF NEW YORK, N. Y.

ATOMIZER.

SPECIFICATION forming part of Letters Patent No. 538,967, dated May 7, 1895.

Application filed September 1, 1894. Serial No. 521,931. (No model.)

To all whom it may concern:

Be it known that I, WILLIAM HUGERSHOFF, a citizen of the United States, residing in the city, county, and State of New York, have invented certain new and useful Improvements in Atomizers, of which the following is a specification.

This invention has reference to certain improvements in the atomizer, for which Letters Patent were granted to me heretofore, No. 514,190, dated February 6, 1894, whereby the same is adapted for vaporizing oily and other heavy medicinal fluids and for returning the so-called "waste" back into the vessel; and 15 the invention consists of an atomizer, which comprises a receiving-vessel for the liquid, a cap applied to the same, a tubular head-piece inserted into the cap and provided with a detachable nozzle, a bulb connected with said 20 head-piece, a block inserted into said head-piece and provided with a conical atomizing-nozzle, and with a supply-tube which extends into the liquid vessel, said supply-tube being arranged with grooves at its upper end within 25 the block, and a valved opening in said block through which air is admitted to the bulb when the same expands, but which is closed when the bulb is compressed so that the air is forced along the grooves of the supply-tube through 30 the discharge-orifice of the atomizing nozzle. The tubular head-piece is provided with an opening below its nozzle, so as to permit the ingress of air in case the outer nozzle should be entirely or partly closed during the application 35 of the atomizer to the parts to be treated.

In the accompanying drawings, Figure 1 represents a side elevation of my improved atomizer. Fig. 2 is a vertical central section of the head-piece with the atomizing device 40 in the same, drawn on a larger scale. Figs. 3 and 4 are horizontal sections drawn on a still larger scale and taken, respectively, on line 3 3 and 4 4, Fig. 2; and Fig. 5 is a side elevation of the upper end of the supply-tube, also 45 drawn on a larger scale.

Similar letters of reference indicate corresponding parts.

Referring to the drawings, A represents the liquid-vessel into which the oily or other medicinal preparation to be atomized is placed.

B is a cap, which is tightly fitted on the neck of the liquid-vessel A.

C is a tubular head-piece, which is screwed into the cap and which is provided with an opening in its base so as to communicate with 55 the neck of the liquid-vessel A.

C' is a detachable nozzle which is rounded-off at its outside, so as to be readily inserted into the nose or other part to which the atomized spray is to be applied. 60

The nozzle C' of the tubular head-piece can be removed so as to give access to the interior of the latter.

D is an elastic bulb, which is not provided with any valve, and which is attached to a 65 socket D', the latter being connected by a tube D' with the tubular head-piece C.

The interior of the head-piece C is either arranged with a shoulder e or it is slightly diminished in width so as to support a block 70 E, which is provided with a central upwardly-extending conical atomizing-nozzle f. The block E is tightly fitted to the interior of the head-piece C, and is provided with a central screw-threaded opening, into which is inserted 75 the upper threaded end of a supply-tube F, which extends through the neck downward into the liquid-vessel A. The upper end of the supply-tube F is located below the central orifice of the atomizing-nozzle f and provided 80 preferably at four equi-distant points with longitudinal grooves f', through which the compressed air that is forced by the bulb D into the head-piece C, is conducted into the interior cavity of the atomizing-nozzle f and 85 through the orifice of the same into the head-piece. The suction through the tube F, which is created by the air passed along the side-grooves f' of the same, draws up the liquid in the vessel A through the supply-tube, and the 90 pressure of the air forces the liquid through the orifice of the atomizing vessel f so as to change the same into spray which is then conducted through the vessel of the tubular head-piece to the part to be treated. This atomizer 95 besides acting by suction on the liquid, also acts to a certain extent by pressure; for the pressure of the air on the surface of the liquid assists in raising the same through the supply-tube F.

The condensed vapors, or so-called "waste," are returned through a valved opening g in the block E into the lower part of the head-piece, and from the same into the liquid-vessel.

sel, whenever the bulb expands and air is drawn in through the valved opening *g* into the bulb. When compressing the bulb the air is forced into the head-piece, and the valve of the opening *g* closed, so that no air can escape except through the longitudinal channels *f'* of the upper end of the supply-tube *F* and the orifice of the atomizing-nozzle *f*. The tubular head-piece *C* is provided below its nozzle *C'* and above the block *E*, with a small air-inlet aperture *h*, through which the air is supplied to the bulb whenever the nozzle *C'* is closed by the parts to be treated. In this case, no air could pass in and consequently the bulb could not expand and would create an injurious suction on the parts. The small air-inlet aperture then supplies the required quantity of air to the bulb without exerting any injurious suction on the parts to be treated.

20 My improved atomizer is especially adapted for atomizing oily and other heavy medicinal fluids, and for returning the condensed vapors or waste back into the liquid-vessel, said waste passing along the conical surface of the atomizing-nozzle and being sucked inwardly through the valved opening in the block when the expansion of the bulb takes place, the waste being then returned for further use into the liquid-vessel, whereby a considerable saving in the medicinal preparation is obtained.

25 By unscrewing the head-piece from the cap and removing the nozzle of the same, the interior block, with its supply-tube, may be removed, the cleaning of all the parts facilitated

30 and the same readily replaced in position for further use.

Having thus described my invention, I claim as new and desire to secure by Letters Patent—

1. In an atomizer, the combination of a liquid-vessel, a tubular head-piece applied to the neck of the vessel and provided with a detachable nozzle, a bulb connected with the head-piece, a block inserted in the head-piece and provided with an atomizing-nozzle and a valved opening, and a supply-tube screwed into the block and provided with longitudinal grooves or channels in the part screwed into said block, substantially as set forth.

2. In an atomizer, the combination, of a liquid-vessel, a tubular head-piece applied to the neck of the same, a detachable nozzle at the upper end of the head-piece, an elastic bulb connected with said head-piece, a block fitted to the interior of the head-piece and provided with an atomizing-nozzle and a valved opening, a supply-tube, inserted into the block and provided with longitudinal grooves or channels, and an air-inlet aperture arranged in the head-piece intermediately between the interior block and the detachable nozzle, so as to permit the air to enter into the bulb when the nozzle of the head-piece should be closed, substantially as set forth.

In testimony that I claim the foregoing as my invention I have signed my name in presence of two subscribing witnesses.

WILLIAM HUGERSHOFF.
